DESIGN FOR A BADGE OR SIMILAR ARTICLE.

SPECIFICATION forming part of Design No. 29,014, dated July 12, 1898.

Application filed May 12, 1898. Serial No. 680,515. Term of patent 3½ years.

To all whom it may concern:

Be it known that I, ARTHUR A. MCRAE, of Attleborough, in the county of Bristol and State of Massachusetts, have invented and 5 produced a new and original Design for a Badge or Similar Article, of which the following is a specification, reference being had to the accompanying drawings, forming part thereof.

10 Figure 1 is a front view of a badge, showing my design. Fig. 2 is a sectional view of the same.

The leading features of my design consist in the raised winged figure resembling the conventional figure of satan, irregular lines resembling rock formations, and central upward-pointing lines resembling flame issuing from a cleft in the rock formation.

15 In the drawings, *a* indicates the raised base; 20 *b b*, irregular raised surfaces resembling rock; *c*, pointed flame-shaped lines giving the con-

ventional appearance of flame extending from the pit *d*; *e*, a winged figure having the conventional appearance of satan; *f*, a fork having barbed points; *g*, a raised figure resembling a skull, and *h* a raised figure resembling an owl. The representation *c* of flame is interposed between the two irregular surfaces *b b*, resembling rock.

25 The design presents to the eye the appearance of satan attending to a subterranean fire.

Having thus described my invention, what I claim as new, and desire to secure by Letters Patent, is—

30 The design for a badge or similar article 35 herein shown and described.

In witness whereof I have hereunto set my hand.

ARTHUR A. MCRAE.
